ELECTRICAL FIXTURE SUPPORTING DEVICE

Filed July 1, 1921

Patented May 15, 1928.

1,669,548

UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL FIXTURE-SUPPORTING DEVICE.

Application filed July 1, 1921. Serial No. 481,734.

My invention relates to electrical fixture supporting devices and connections therefor.

One of the objects of my invention is to provide an improved fixture supporting device in which the fixture can be readily connected and disconnected with respect to the receptacle both electrically and mechanically.

A further object of my invention is to provide an improved fixture supporting device in which thief-proof means are provided for preventing the removal of the fixture by an unauthorized person.

A further object of my invention is to provide such a device which will be simple in construction, cheap to manufacture and durable and efficient in use.

Further objects will appear from the detailed description to follow and from the appended claims.

20 In the drawings in which an embodiment of my invention is shown—

Fig. 1 is a vertical axial section showing a receptacle, a fixture and a connecting bracket and plug;

25 Fig. 2 is a front view showing the receptacle and face-plate;

Fig. 3 is an elevational view showing the bracket and plug-in device;

Fig. 4 is a front view of the bracket;

30 Fig. 5 is a section on the line 5—5 of Fig. 3.

Fig. 6 is a bottom plan view of the construction shown in Fig. 3; and

Fig. 7 is a view showing a different form of releasing mechanism.

35 The construction shown in the drawings comprises a fixture 11, a receptacle 12, a plug-in device 13, for electrically connecting the fixture with the receptacle, and a mechanical connecting member or bracket 14 for mechanically connecting the fixture with respect to the receptacle.

40 The plug-in device 13 is carried by the connecting bracket 14, being bodily slidably mounted thereon to permit the necessary movement of the connecting bracket 14 to make the mechanical connection without interfering with the insertion of the contact blades 15 of the plug-in device 13 in the openings 16 provided in the receptacle 12.

45 The mechanical connector member or bracket 14 is secured to the supporting plate 17 (which may be a sort of cover for the outlet box (by means of a pair of hook members 18 at the upper end of the bracket, and

55 a T-shaped headed member 19 at the lower

end of the bracket. The supporting plate 17 is provided with a pair of slots 20 to receive the hook members 18, and with a notch 21 adjacent the lower end of the receptacle to receive the headed member 19. The connection of the bracket 14 with the supporting plate 17 is effected by two movements, first a movement of insertion to bring the hook members 18 and headed member 19 back of the plate 17, and second, a downward movement to engage the hook members 18 and headed member 19 with the supporting plate 17. The sliding movement between the plug-in device 13 and the connecting bracket 14, hereinbefore referred to, permits the downward movement of the connecting bracket 50

65 without interference from the engagement of the blades 15 in the openings 16. The sliding connection of the plug-in device 13 with the connecting bracket 14 is effected by 70 means of a pair of lugs 22 struck up from the material of the bracket 14, the plug being held between the body portion of the bracket and these lugs. The bracket 14 may be a sheet metal stamping, the hook members 18, 75 headed member 19, and the lugs 22 being formed as integral parts of this stamping.

80 In order to positively hold the bracket 14 in connected position on the plate 17, a spring latch member 23 is provided having an inwardly bent portion 24 which snaps in underneath the insulating base 25 of the plug-in device 13 when the bracket 14 is moved down to the connected position with respect to the plate 17.

85 When this spring latch 23 snaps into latching position it positively prevents the bracket 14 from being raised, and thus prevents it from being disconnected.

90 In order to release the positive spring latch 23, a bell-crank lever 26 is provided, pivoted at 27 to the bracket 14, one arm of which bell-crank engages the end 28 of the spring latch 23, and the other arm of which may be connected to a pull member 29.

95 In order to prevent the release of the spring latch 23 by an unauthorized person and thus prevent the theft of the fixture, the construction may be such that a key is necessary to effect the operation of the pull member 29. For this purpose, a threaded connecting member 29^a is secured to the end of the pull member 29, this pull member 29^a being slidably mounted in a tubular member 29^b, secured to the canopy 30. The member 100

105

110

29^a is provided with a shank portion 31 having a left-hand thread, for engagement with the left-hand threaded socket portion 31^a of the key member 31^b.

5 In order to release the latch, the key 31^b is inserted into the tubular member 29^b and screwed onto the screw-threaded shank 30^a, the key is then pulled down, pulling down with it the pull member 29, and rocking the bell-crank lever 26 to push the spring latch 23 outwardly, to release the bracket 14 for upward movement. The fixture and bracket can then be lifted upwardly and pulled outwardly, and thus disengage from the supporting plate 17.

10 In order to limit the movement of the bell-crank 26, the stop lug 36 may be provided, struck up from the material of the bracket 14.

15 20 The canopy 30 which supports the fixture 11 may be secured to the bracket 14 by means of a transversely extending strap 37 having its ends secured to the canopy 30, and its intermediate portion secured to the bracket 14, by means of a screw 38. The bracket 14 may be provided with an upwardly extending post 39, which is used in making the connection with certain forms of fixtures.

25 30 A suitable ornamental finishing plate or escutcheon 40 may be provided in front of the supporting plate 17.

35 In Fig. 7 is shown a construction in which the bell-crank-lever 26 which operates the spring latch 23 is itself operated by means of a pull chain 41, the upper end of which is connected to the bell-crank, and which extends downwardly through an opening 42 in the canopy 30.

40 45 Having thus described my invention what I claim as new and desire to secure by Letters Patent of the United States is:

1. The combination with a fixture and a receptacle, of means for electrically connecting the fixture with respect to the receptacle, and mechanically connecting and supporting the fixture with respect to the receptacle, said means comprising a supporting member, a connecting bracket, and a plug-in device having contacts for engagement with the receptacle contacts, mounted for bodily sliding movement on said bracket, said bracket and supporting member being provided with interengaging means whereby said bracket may be connected to said plate by movement towards said receptacle, and laterally with respect thereto, means for

holding the bracket in connected position, comprising means for preventing relative sliding movement between said bracket and plug-in device, a canopy for housing said bracket, and means operable from the outside of said canopy for controlling said preventing means.

2. The combination with a fixture and a receptacle, of means for electrically connecting the fixture with respect to the receptacle, and mechanically connecting and supporting the fixture with respect to the receptacle, said means comprising a supporting member, a connecting bracket, and a plug-in device having contacts for engagement with the receptacle contacts, mounted for bodily sliding movement on said bracket, said bracket and supporting member being provided with interengaging means whereby said bracket may be connected to said supporting member by movement towards said receptacle, and laterally with respect thereto, means for holding the bracket in connected position, comprising means for preventing relative sliding movement between said bracket and plug-in device, a canopy for housing said bracket, and means operable from the outside of said canopy for controlling said preventing means, said last means having provisions whereby it may be operated from different angles.

3. The combination with a fixture and a receptacle, of means for electrically connecting the fixture with respect to the receptacle, and mechanically connecting and supporting the fixture with respect to the receptacle, said means comprising a supporting member, a connecting bracket, and a plug-in device having contacts for engagement with the receptacle contacts, mounted for bodily sliding movement on said bracket, said bracket and supporting member being provided with interengaging means whereby said bracket may be connected to said supporting member by movement towards said receptacle, and laterally with respect thereto, means for holding the bracket in connected position, comprising means for preventing relative sliding movement between said bracket and plug-in device, a canopy for housing said bracket, and means operable from the outside of said canopy for controlling said preventing means, said last means comprising a bell-crank.

In witness whereof, I have hereunto subscribed my name.

REUBEN B. BENJAMIN.
